ELECTRIC IRON

Frank Kuhn, Detroit, and Laurence H. Thomas,
Birmingham, Mich., assignors to American
Electrical Heater Company, Detroit, Mich., a
corporation of Michigan

Application April 28, 1930, Serial No. 448,098

6 Claims. (Cl. 219—25)

This invention relates to electric heaters and has particular reference to thermostatically controlled heaters.

The invention while capable for use in connection with various types of heaters finds particular utility when used in connection with electric irons and has as one of its objects to simplify, render more efficient and improve generally the construction of irons.

10 A further advantageous feature of this invention resides in the provision of an electric iron having a thermostatic switch assembly including adjustable regulating means for controlling the operation of the switch mounted upon the iron in such a manner as to permit the same to be readily assembled with and removed from the iron as a unit.

Other objects of the invention reside in the peculiar construction of the iron which permits 20 the same to be economically manufactured and assembled with facility. These objects will be made more apparent as the description proceeds, especially when considered in connection with the accompanying drawing, wherein:

25 Figure 1 is a side elevational view partly in section of an iron constructed in accordance with this invention.

Figure 2 is a fragmentary plan view of the construction shown in Figure 1.

30 Figure 3 is an end elevational view of the iron with certain parts removed for the sake of clearness.

Figure 4 is a sectional view taken on the line 4—4 of Figure 2.

35 Referring now to the drawing, it will be noted that there is illustrated in Figure 1 an electric iron 10 having a heat distributing base 11, a heating element 12 seated upon the base 11, a pressure plate 13 resting upon the heating element and a hood or cover 14 for inclosing the heating element, pressure plate and the other parts of the heater to be presently described. The heating element 12 comprises a coil 15 having one end 16 secured to a suitable terminal

40 supporting bracket 17 which in turn is suitably secured to the heating element so as to form a unit therewith. Secured to the upper portion of the bracket 17 as at 18 is a suitable terminal 19 adapted to project through an insulator block

45 20 and through the cover 14 of the iron. The opposite end 21 of the heater coil is connected to a cooperating terminal supporting bracket 22 comprising a base portion 23 secured to the heating element and a terminal supporting portion

50 24 secured to the base portion 23 and insulated therefrom. As shown in Figure 3, the base 23 and terminal supporting portion 24 of the bracket 22 are formed with lateral projecting terminal portions 25 and 26, respectively, adapted to be

ly described. The portion 24 of the bracket 22 supports a terminal 28 which extends through the insulator block 20 in the same manner as the cooperating terminal 19. Thus, it will be observed that an electric circuit is provided through the heating element and thermostatic switch.

5 The thermostatic switch 27 regulates the temperature of the iron by controlling the electric circuit through the heating element and comprises 10 a pair of cooperating thermostatic strips 29 and 30 arranged within a recess 31 in the base plate 11 and having cooperating contact points 32 and 33 adapted to engage each other when the iron falls below a predetermined temperature to close 15 the circuit to the heating element. Connected to the opposite ends of the thermostatic elements 29 and 30 and insulated from each other is a pair 20 of terminal members 34 and 35 having upwardly extending portions detachably secured to the terminals 25 and 26, respectively, by means of the screws 36. The ends of the thermostatic elements opposite the contact points 32 and 33 together with the terminal members 34 and 35 are secured to the lower leg 37 of a substantially U-shaped bracket 38 by means of a single fastener element 39. The base 40 of the bracket extends upwardly through suitable aligned slots formed in the heating element and pressure plate and the upper leg 41 of the bracket is secured by means 25 of a stud 42 to a plate 43 which, as shown, rests upon the pressure plate 13. The upper leg 41 of the bracket is preferably substantially parallel to the lower leg 37 and extends beyond the same as clearly illustrated in Figure 1. The portion of the 30 leg 41 extending beyond the leg 37 is formed with a threaded opening 44 therein for adjustably receiving a suitable bushing 45. The interior of the bushing is also threaded and is adapted to adjustably receive a threaded element 46 terminating below the leg portion 41 in an enlarged 35 substantially flat head portion 47 adapted to engage a suitable projection 48 on the lowermost thermostatic strip 29. The arrangement is such that as the temperature of the iron rises above 40 a certain predetermined point, the head portion 47 on the adjustable element engages the projection 48 and prevents further movement of the lowermost thermostatic strip 29. As a consequence, the upper strip 30 moves away from the 45 strip 29 with the result that the contact points 32 and 33 are separated and the circuit to the heating element broken. It will be obvious from the foregoing description that the temperature at which the thermostat functions to break the 50 circuit to the heating element may be regulated by moving the head portion 47 axially toward or away from the projection 48. The above adjustment is accomplished from a point exteriorly of the cover 14 by means of a control arm 49 secured

55 60 to the cover 14.

to the upper end of the adjustable element 46. The initial position of the enlarged portion 47 relative to the projection 48 is determined by means of adjusting the sleeve 45 relative to the leg portion 41. As shown in Figure 1, the opening in the cover through which the adjusting element 46 passes is of sufficient dimension to permit the passage therethrough of a suitable tool. With this construction the bushing 45 may be 10 adjusted from without the iron by merely detaching the control arm 49.

In order to limit the extent of adjustment of the element 46, we provide a suitable stop 50 in the form of a pin secured to the leg portion 41 and depending therefrom in the path of travel of a lateral projection 51 secured to the head portion 47. Thus, it will be observed that adjustment of the element 46 is limited to one complete revolution thereof. In order to compensate for any back 20 lash between the teeth of the adjustable element 46 and the sleeve 45, we provide a flexible strip 52 having one end secured to the leg portion 41 by means of the stud 42 and the opposite end flexed downwardly from the leg portion 41 and 25 engageable with the head 47 to normally urge the same to its lowermost position. The flexible strip 52 is held from lateral movements by engagement with the stop 50 as shown in Figure 1 of the drawing.

30 As shown in Figure 4, the switch unit, hereinbefore discussed, pressure plate, heating element and base plate are secured in assembled position by means of fastener elements 53 having the head portions thereof engaging the plate 43 beneath 35 the cover 14 so as to be concealed thereby and having the shank portions extending through aligned openings in the aforesaid plate and threadedly engaging the openings in the base plate. The upper end of the stud 42 for securing 40 the bracket 38 to the plate 43 preferably projects through the cover 14 of the iron and threadedly receives a suitable nut 54 which serves to secure the cover in assembled position. The foregoing arrangement is such as to permit the iron to be 45 readily assembled and economically manufactured.

What we claim as our invention is:

1. An electric iron assembly having in combination, a base plate, a pressure plate above the base plate, a heating element interposed between the aforesaid plates, means for securing said plates and heating element together as a unit, means responsive to variations in temperature changes for controlling the operation of the heating element including a switch insertable through a recess in the pressure plate to a position in close proximity to the base plate, a bracket member carrying said switch, and means removably securing the bracket to the pressure plate independent of the aforesaid fastening means whereby the bracket member and switch are removable as a unit through said recess without disassembling the plates.

2. An electric iron assembly having in combination, a base plate, a pressure plate above the base plate, a heating element interposed between said plates, fastening means for clamping said plates and heating element together, a bracket removably secured to the upper side of the pressure plate independent of the fastening means aforesaid and having a portion extending downwardly through a recess in said plate to

a position in close proximity to the base plate, means for controlling the operation of the heating element including a thermostatic switch carried by the lower portion of said bracket and removable therewith through the recess aforesaid in the pressure plate in the assembled relationship of the latter with the base plate.

3. An electric iron having in combination, a base plate, a pressure plate above the base plate, a heating element interposed between the plates, a bracket removably secured to the pressure plate and having a portion extending downwardly in close proximity to the base plate, a thermostatic switch for the heating element removable as a unit with the bracket and secured to the lower portions thereof so as to be in heat conducting relation to the base plate, a cover for the assembly, means carried by the bracket for removably securing the cover in place, and adjustable means also carried by the bracket and accessible for manipulation exteriorly of the cover for regulating the temperature at which the thermostat operates.

4. An electric iron assembly having in combination, a base plate, a pressure plate above the base plate, a heating element interposed between said plates, a thermostatic switch for the heating element located within a recess in the base plate, a bracket detachably secured to the pressure plate and having a portion extending downwardly through a recess in the pressure plate of sufficient dimension to permit passage of the switch therethrough in the assembled relation of the plates, and means for securing the switch to the bracket.

5. An electric iron assembly having in combination, a base plate, a pressure plate above the base plate, a heating element interposed between the aforesaid plates, temperature responsive means for controlling the operation of the heating element including a switch insertable through a recess in the pressure plate to a position in close proximity to the base plate, a bracket having a portion extending downwardly through the recess in the pressure plate and secured to said switch, and means for detachably securing the bracket to the pressure plate whereby the bracket and switch may be removed as a unit through the recess in said pressure plate without disturbing the position of the latter relative to the base plate.

6. An electric iron assembly having in combination, a base plate, a pressure plate above the base plate, a heating element interposed between the aforesaid plates, temperature responsive means for controlling the operation of the heating element including a switch insertable through a recess in the pressure plate to a position in close proximity to the base plate, a bracket having a portion extending downwardly through the recess in the pressure plate and secured to said switch, means for detachably securing the bracket to the pressure plate whereby the bracket and switch may be removed as a unit through the recess in said pressure plate without disturbing the position of the latter relative to the base plate, and means for regulating the operation of the switch from a point above the pressure plate including an adjustable member carried by said bracket.
